INVENTOR.

BY

Richard B. Oliver.

ATTORNEY.

UNITED STATES PATENT OFFICE.

EDWARD P. JONES, OF BRECKENRIDGE, COLORADO.

HAMMER DRILL.

Application filed September 3, 1921. Serial No. 496,505.

To all whom it may concern:

Be it known that I, EDWARD P. JONES, a citizen of the United States, residing at Breckenridge, in the county of Summit 5 and State of Colorado, have invented certain new and useful Improvements in a Hammer Drill, of which the following is a specification.

This invention relates to means for operating a drill for boring rock and mineral and has for its object to provide an essentially high powered mechanism which will operate a drill by a rotary motion, and a driving action, means being provided for 15 effecting both actions from a rotary spindle.

With the above and numerous other objects in view the invention consists in certain novel features of construction and the combination and arrangement of parts as 20 will be hereinafter more fully described and claimed.

In the drawings:—

Figure 1 is a top plan view of the operating means,

25 Figure 2 is a front elevation thereof,

Figure 3 is a longitudinal sectional view taken therethrough,

Figures 4, 5 and 6 are sections taken approximately on the lines 4—4, 5—5, and 30 6—6 respectively of Figure 3,

Figure 7 is a perspective view a tool engaging drum, and

35 Figure 8 is a detailed perspective view of a ratchet cylinder used therewith.

Referring to the drawing in detail it will be seen that 1 designates any suitable support upon which is mounted a cylinder 2 having its rear end open and its forward end partially closed by the wall 3. A head 4 is associated with the rear end of the cylinder 2 so as to receive the rotary spindle 5 which is suitably journaled therein and extends a distance into the cylinder 2 as 40 shown to advantage in Figure 3. The inner end of this spindle 5 is provided with longitudinally extending ribs 6 which are received in corresponding longitudinally extending grooves 7 provided in the hollow hammer 8 which is rotatably mounted with-

45 in the cylinder 1 and is also capable of reciprocating therein. This hammer 8 is provided on its periphery with a plurality of cam grooves 9 which are engaged by rotary 50

dogs 10 passing through suitable apertures in the wall of the cylinder 2 and held in place by screw caps 11. Thus it will be seen that as the spindle 5 is rotated a rotary and sliding action will be imparted to the hammer 8 so that it will revolve and reciprocate simultaneously. An extension 13 having a 60 diameter considerably less than that of the hammer 8 is provided at its forward end so as to extend through the opening in the wall 3.

A tool receiving casing 14 is suitably 65 mounted on the forward end of the cylinder 2. Preferably this casing 14 is held in place by a pair of rods 15 which extend through the flange 16 of the casing 14 and through the head 4 as shown to advantage in Figure 70 1 and these rods are provided with threaded ends so as to receive suitable nuts whereby both the heads 4 and the casing 14 may be snugly held in engagement with the ends of the cylinder 2. The forward end of the 75 casing 14 is provided with an opening 17 through which one end of the drill tool will be positioned. This drill tool indicated by the dotted line configuration 18 is held in place by the bail 19 which is suitably journaled or pivotally mounted in a cap 20 carried on top of the cylinder 2. As shown to advantage in Figure 2 the bail 19 is provided with the jaws for receiving the drilling tool. This bail also is in engagement 80

85 with a lever 21 suitably fulcrumed on the casing 14 so that the bail may be readily disengaged from the drilling tool 18 when so desired by pushing downwardly upon its rear end as will be readily understood from 90 an inspection of the drawings. A tool operating drum 23 is rotatably mounted in the casing 14 and is provided with an annular series of ratchet teeth 24 intermediate its ends which are engaged by a spring 95 pressed dog 25 and it will be noted that these ratchet teeth 24 and the dog 25 are so constructed that the drum 23 will be free to operate in one direction only. The forward end of the drum 23 is provided with a non-circular opening 25' which receives a corresponding end of the drilling tool 18 as will be readily understood by those skilled 100 in the art. A suitable aperture 26 is provided in the drum 23 for receiving the 105

spring pressed pawl 27 which engages the

annular series of ratchet teeth 28 provided on the outer periphery of the cylinder 29 which is rotatably mounted within the drum 23 adjacent its rear end as shown to advantage in Figure 3. The extension 13 of the hammer 8 extends into this cylinder 29 and this extension is provided with a cam groove 30 which is engaged by a spring pressed dog 31 mounted in the aperture 32 of the cylinder 29.

It will be noted by referring to Figure 3 of the drawing, that cam grooves 9 are shaped to cause a rapid forward propulsion of hammer 8 and extension 13 as spindle 5 is rotated, thereby giving a sharp blow to the drill at each revolution. It will also be seen that the pitch of cam groove 30 is greater than the pitch of cam grooves 9. As hammer 8 and extension 13 are propelled forward and rotated cam groove 30 will function to rotate the drill carrying means at proper intervals to turn the drill to a new position after or during each blow as may be desirable under working conditions. If the pitches of grooves 9 and 30 were the same, there would be no tendency for 29 to turn. As these pitches differ, however, there will be a thrust exerted on 31 which may be resolved into an end thrust taken up in the structure, and a thrust causing rotation of 29 with 13, but at a relatively different speed on movement of 13 in one direction, and will cause rotation of 29 in a reverse direction from the rotation of 13 on its return movement. An oscillating movement of member 29 will therefore be caused in accordance with the shape of groove 30. Due to the ratchet connection between member 29 and 23, member 23 is rotated intermittently in one direction only and causes turning of the drill. This rotation or turning movement of the drill may be caused either on the forward or return movement of hammer extension 30.

Having described a preferred embodiment

of my invention what is desired to be secured by Letters Patent and claimed as new is:

1. In means for operating a boring tool, a hammer mounted to receive a rotary and a longitudinal movement, an extension provided thereon, a tool engaging element provided with an annular series of ratchet teeth on its exterior periphery, a dog for engaging the ratchet teeth so as to prevent the movement of the tool engaging element in one direction, a cylinder rotatably mounted within the tool engaging element and provided with an annular series of ratchet teeth, a spring pressed dog mounted in the tool engaging element and adapted to engage the ratchet teeth of the cylinder, a spring pressed dog mounted within the cylinder and adapted to engage a cam groove provided in the extension of the hammer. 55

2. A drill machine comprising rotary reciprocating means; rotary drill carrying means; a ratchet drive member; a cam groove carried by said first mentioned means; and means co-acting with said cam groove to drive said ratchet drive member and thereby impart intermittent rotary motion to said drill carrying means. 70

3. A drill machine comprising a rotary cylindrical body portion; rotary drill carrying means; a driving cam groove in said body portion co-acting with a fixed member to cause a reciprocating motion of said body portion thereby causing a hammer blow to be struck on said drill; a ratchet drive member for rotating said drill carrying means; and means for driving said ratchet member from said body portion comprising a cam groove of relatively greater pitch than the pitch of the cam groove in said body portion. 75 80 85

In testimony whereof I affix my signature.

EDWARD P. JONES.
